UNITED STATES PATENT OFFICE.

JOSEPH WAKEFIELD AND ARTHUR LAMB, OF LONDON, ENGLAND.

SAFETY-RAZOR-BLADE-HONING DEVICE.

1,367,108.

Specification of Letters Patent.

Patented Feb. 1, 1921.

Application filed February 17, 1920. Serial No. 359,359.

To all whom it may concern:

Be it known that we, JOSEPH WAKEFIELD and ARTHUR LAMB, both subjects of the King of Great Britain and Ireland, and residing at London, England, have invented certain new and useful Improvements in Safety-Razor-Blade-Honing Devices; and we do hereby declare the following to be a full, clear, and exact description of the invention, such as will enable others skilled in the art to which it appertains to make and use the same.

This invention relates to improvements in honing devices for safety razor blades and refers more particularly to that type in which the blade is secured to a holder removably attachable to a rotatable pivot so as to enable the blade holder to be reciprocated through a curved path above the honing surface, the holder being so mounted as to permit of its rotation when the direction of movement is reversed.

The object of the present invention is an improved and simplified construction of honing devices of the type described which is adapted for use with any type of blade (single or double edge) in which the blade holder may be easily and quickly adjusted with respect to the operating surface of the honing stone to obtain the best results, while the method of mounting the blade holder permits of its use by the most inexperienced persons without risk of injuring or damaging the blades.

And in order that our said invention may be more clearly understood, we will now proceed to describe the same with reference to the accompanying drawing, which shows by way of example an apparatus constructed according to one embodiment of our invention.

Figure 1 is a side elevation of the apparatus or device with the holder in position.

Fig. 2 is a plan showing the holder in one extreme position in full lines and dotted in the other extreme position.

Fig. 3 is a front elevation with the blade holder removed.

Figs. 4 and 5 are elevations of two forms of blade holders.

Fig. 6 is an enlarged detail partly in section.

The same letters of reference are employed to denote the same parts in all the views.

a is a plate of metal or other suitable material to which is attached another plate *b* provided with downwardly turned ends *b*¹, which enable the device to be easily held in a position with one hand. Mounted upon the platform *a* is the honing stone *c*, which in the present instance is provided with diagonally extending grooves *c*¹. The plate *a* is extended at *a*¹ and through a perforation in this extended portion *a*¹ passes the supporting column for the holder. This is illustrated in detail at Fig. 6. *d* is an externally screw threaded tube, which is adapted to be adjusted in position vertically with respect to the plate *a*¹ by means of nuts *e* coming above and below the plate, any appropriate washers being added for facilitating adjustment. *f* is a rod or pillar, the reduced portion *f*¹ of which passes down the tube *d*, and is held in position therein but so as to be rotatable by means of the washer *g* and screw *g*¹. *h* is a rod connected by a suitable ball joint *m* to the top of the column *f*, in such a way that the rod can be swung vertically upward or rotated about its axis. The holder for the blade two forms of which are shown at Figs. 4 and 5 is provided with a tubular portion *p* adapted to telescope or slide over the rod *h*. It is also provided with a grooved collar *q* and a handle *r*. Attached to the outer edge of the plate *a* is a guide *s* provided with two uprights *s*¹, *s*¹ and a hinged top bar *s*², the end of which when the device is closed is adapted to be engaged by a suitable hinged loop or clip *s*³.

The holder shown at Fig. 4 is provided with plates *p*¹ between which the blade, for instance a single edged blade is inserted.

The holder as shown at Fig. 5 is furnished with a lower fixed plate *p*² and a hinged plate *p*³, which latter is so mounted that it can be longitudinally slid for a short distance as well as turned upon its pivot, and the lower plate *p*² is provided with a stud *p*⁴ which is adapted to pass into a key hole slot *p*⁵ so that when the blade is placed in position and the plate *p*³ is turned down and slid longitudinally, the blade can be locked in position. The plate *p*³ is turned up at each end at *p*⁶ to facilitate its manipulation.

The general operation of the device will be readily understood. The blade is placed in position in the required holder for in-

stance in the one illustrated at Fig. 4, which is also shown in use in Figs. 1 and 2. The end of the tube p is then pushed on to the rod h and then the top member s^2 of the 5 guide is turned down into the position shown in full lines in Fig. 3, in which position it is secured by the loop or clip s^3 . The device is now held in one hand by means of the downwardly turned portion b^1 of the 10 plate b and the holder is drawn backward and forward by means of the handle r , the edge of the blade being turned in the forward direction.

It is found in practice that after the blade 15 has been drawn a very few times across the honing stone, the blade is very efficiently honed or set and it can be removed and a fresh blade placed in position. The adjustment for the pillar f explained with 20 reference to Fig. 6 enables the height to be very accurately regulated so that the edge of the blade is preferably flat and true with regard to the surface of the stone.

An important additional advantage is secured by providing the diagonal grooves c^1 25 on the surface of the stone c a more efficient result being secured than when the surface of the stone presents a dead level.

The holder for the reception of the blade 30 may be provided with one fixed plate and one hinged plate between which the blade is clamped in any suitable way. In some cases one of the clamping plates may be made removable so that it can be exchanged 35 for another plate according to the nature of the blade which is to be sharpened.

What we claim as our invention and desire to secure by Letters Patent of the 40 United States of America is:—

1. A device for honing the blades of razors comprising a framework carrying a honing stone, a vertically adjustable pillar mounted rotatably on said framework, a rod connected to the top of said pillar by 45 means of a universal joint, a blade holder removably connected to said rod and guiding means toward the free end of said blade holder for guiding the same during its movement through an arc, for the purposes described.

2. A device for honing the blades of razors comprising a framework carrying a honing stone, a vertically adjustable externally screwed tube mounted on said frame, a pillar rotatable in said tube a rod 50 connected to the top of said pillar by means

of a universal joint, a blade holder removably connected to said rod and guiding means toward the free end of said blade holder for guiding the same during its 60 movement through an arc, for the purposes set forth.

3. A device for honing the blades of razors comprising a framework carrying a segment-shaped honing stone and having 65 a screwed hole at one end of said framework, an externally threaded tube in said hole, provided with lock nuts on opposite sides adapted to lock said tube in any vertically adjusted position in said hole, a pillar 70 rotatable in said tube and formed with a shoulder adapted to engage the upper end of said tube, a rod connected to the top of said pillar by means of a universal joint, a blade holder removably connected to said 75 tube and a guide engaging said blade holder intermediate its ends and adapted to maintain the same in a plane parallel with the surface of the honing stone and to limit its movement through an arc in opposite directions, for the purposes set forth.

4. A device for honing the blades of razors comprising a framework carrying a honing stone, a vertically adjustable pillar mounted rotatably on said framework, a 85 rod connected to the top of said pillar by means of a universal joint, a blade holder removably connected at one end to said rod and provided at the other end with a handle, a grooved collar on said holder intermediate its ends and an arc shaped guide on said frame with which said collar engages during its movement through the arc of a circle for the purposes set forth.

5. A device for honing the blades of 95 razors comprising a framework carrying a honing stone, a vertically adjustable pillar mounted rotatably in said frame, a rod connected to the top of said pillar by means of a universal joint, a blade holder removably 100 connected to said rod, an arc shaped guide on said frame engaging the blade holder during its movement through the arc of a circle, said guide having a hinged top bar to enable said blade holder to be disengaged 105 from said guide, and means for holding the frame during honing operations, for the purposes set forth.

In witness whereof we affix our signatures.

JOSEPH WAKEFIELD.
ARTHUR LAMB.
